UNITED STATES PATENT OFFICE.

WALTER J. BRUNGER, OF BOISE, IDAHO.

WASHING-MACHINE.

1,185,766.

Specification of Letters Patent. Patented June 6, 1916.

Application filed July 19, 1915. Serial No. 40,736.

To all whom it may concern:

Be it known that I, WALTER J. BRUNGER, a citizen of the United States, residing at Boise, in the county of Ada and State of Idaho, have invented certain new and useful Improvements in Washing-Machines, of which the following is a specification, reference being had to the accompanying drawings.

13 This invention relates to washing machines, and has for its primary object to provide an improved washer for flat work such as sheets, pillow slips, towels, table cloths, and like articles of fabric, whereby said articles may be quickly and thoroughly washed without subjecting the same to excessive wear.

18 The invention has for a further object to provide a machine of the above character having improved means for automatically feeding the fabric articles to a plurality of reservoirs and finally delivering the same to a drying and ironing machine.

23 It is another object of my invention to provide improved means for automatically feeding a washing compound to certain of the reservoirs.

28 An additional object of the invention resides in the provision of means whereby the washing liquid is forcibly expelled against the fabric article upon its entrance into the reservoir and the fabric thoroughly permeated thereby to remove the particles of dirt.

33 With the above and other objects in view, my invention consists in the novel features of construction, combination, and arrangement of parts to be hereinafter more fully described, claimed, and illustrated in the accompanying drawings, in which,

38 Figure 1 is a diagrammatic side elevation of a washing machine constructed in accordance with the preferred embodiment of my invention; Fig. 2 is a top plan view of the forward or feed end of the machine; Fig. 45 3 is a section taken on the line 3—3 of Fig. 1; Fig. 4 is a section taken on the line 4—4 of Fig. 2; Fig. 5 is a fragmentary plan view of the rear end portion of the machine; Fig. 6 is an enlarged vertical section through

50 one of the reservoirs; Fig. 7 is an enlarged elevation illustrating the means for adjusting and supporting the delivery rolls which remove the washed articles from the endless tapes for delivery to the ironing machine; and Fig. 8 is a detail perspective view of the

means for adjusting or tensioning the article holding cords.

Referring in detail to the drawings, 5 designates a series of reservoirs, preferably six in number, which are mounted and supported in a suitable framework of any desired construction. In each of these reservoirs, a longitudinally grooved or corrugated roller 6 is mounted, the gudgeons upon the ends of such roller being journaled in suitable water tight bearings provided upon the opposite end walls of the reservoirs. Upon the frame legs 7, a longitudinally extending shelf or support 8 is secured, said shelf being made up of a plurality of sections. The reservoirs 5 are preferably arranged in pairs and the supporting legs 7 are securely bolted together. Upon the longitudinally extending support 8, centrifugal pumps 9 are mounted, one of said pumps being provided for each of the reservoirs 5. A supply pipe 10 connects the pump cylinder to the bottom of the reservoir while the discharge pipe 11 leads from the opposite side of the pump cylinder upwardly through the reservoir to a point 80 slightly above the roller 6 where said discharge pipe communicates with the transversely disposed jet pipe or tube 12, the purpose of which will be hereinafter fully pointed out.

85 A plurality of endless feed tapes or ribbons 13 extend around and under the several rollers 6. Upon the opposite end walls of each reservoir 5 and at one side of the roller 6 therein, the ends of peripherally flanged rollers 14 are journaled. These rollers guide or direct the tapes or ribbons 13 after the same leave the roller 6 in one reservoir to the roller 6 of the next succeeding reservoir. Any desired number of feeding tapes 13 90 may be employed, and it will be understood that the rollers 14 are each provided with a multiplicity of spaced annular flanges between which the tapes are received and whereby said tapes are properly spaced 95 from each other.

100 In spaced relation to the forward end of the machine, the smooth roller 15 is rotatably mounted in a suitable support secured to the main frame structure. Below this roller and between the same and the first of the guide rollers 14, a series of rollers 16 are mounted, over which the lower stretches of the feed tapes 13 successively pass. Weighted sheaves 17 are engaged upon the several 110

tapes and alternately arranged between the rollers 16, and by their gravity action, serve to maintain the tapes under tension or tight upon the several rollers. At the feed end of 5 the machine and adjacent to the roller 15, the inclined smoothing board 18 is arranged, over which the tapes pass. Upon this board, the articles to be washed are placed in a flattened condition, and said articles are carried from the board by the tapes 13 into 10 the first of the tanks or reservoirs 5.

After passing around the several rollers 6 and out of the rear end reservoir 5, the tapes 13 pass between the pairs of presser rollers 15 15 19 and 20, respectively. The lower rollers are preferably constructed of metal while the upper rollers 20 are made of heavy galvanized iron and covered or padded with fabric, preferably duck. These rollers 20 are mounted at their ends in spring pressed 20 bearings, as shown at 21, so that the same are yieldably forced downwardly upon the tapes and on the articles of fabric which are carried thereby. After leaving the presser 25 rollers, the tapes pass around a roller 22 and then downwardly around the lower roller 23. The roller 22 is provided with spaced flanges in a similar manner to the rollers 14 while the lower roller 23 is smooth. 30 A supporting roller 24 for the tapes is also mounted upon the machine frame intermediate of its ends and at the forward end of the machine, the guide roller 25 is journaled. From this latter roller, the tapes pass upwardly and over the series of rollers 16.

In order to retain the articles of fabric upon the feeding tapes as the latter pass over the several rollers 14 and into and out of the reservoirs, I provide the heavy tightly 40 woven or twisted cords 26 which are also endless and correspond in number with the number of the tapes 13. The upper stretches of these cords are supported and guided by a series of rollers 27 mounted in the frame 45 of the machine. In order to maintain said cords in a taut condition and also in contact with said friction rollers, the tightening devices 28 are provided at the forward end of the machine, said devices being fulcrumed 50 intermediate of their ends, as at 29, upon a rod fixed in the machine frame and having their inner lower ends increased in thickness or weighted as at 30. The upper ends of 55 said tightening member bearing upwardly against the several cords 26, act to prevent the same from sagging and maintain the cords in a taut condition. It will be observed that the front and rear rollers 27 are disposed forwardly and rearwardly, respectively, of the front roller 14 and the presser rollers 20. Thus, as indicated by the arrow in Fig. 1, the several endless cords 26 pass over the forward roller 27 and then downwardly and inwardly around the forward 60 roller 14, at which point the cords engage

with the respective tapes 13 and pass with said tapes around the several rollers 6 and through the tanks 5. The lower stretches of the cords 26 also pass between the presser rollers 19 and 20 and then upwardly around the rear roller 27 while the tapes continue a direct rearward movement around the roller 22 and then downwardly around roller 23 and again forwardly and upwardly over the feed table 18.

Upon the rear end of the machine frame, a pair of arms 31 are pivotally mounted at one of their ends for swinging movement in an arc concentric with the roller 22. The pivot studs on which said arms are mounted are threaded to receive suitable clamping nuts whereby the arms may be securely clamped and held in an adjusted position. In these spaced arms, the bearing trunnions 80 are journaled. The roller 32 is of substantially the same diameter as the roller 22 while the roller 33 is of somewhat smaller diameter. This latter roller is preferably adjustable longitudinally upon the arms 31 toward or 85 away from the roller 32. A second series of endless cords 34 extend around the rollers 22 and 33, and are adapted to receive the washed articles of fabric from the tapes 10 and deliver the same to a rearwardly extending ribbon feed 35 which is a part of ironing machine, which, in turn, feeds said articles to a drying and ironing machine (not shown). The rollers 22 and 32 are approximately one inch apart and the endless 90 cords 34 extending around the roller 22 and 33 are disposed intermediate of the endless tapes 13. These cords lift the flat pieces from the tapes 13 after passing between the ringer rolls 19 and 20, the wet flat pieces 105 sticking to the wet tapes. The cords act to lift the flat pieces and remove the same from the tape so that their delivery to the ribbon feed 35 is assured. Endless tapes 34' are also engaged upon the rollers 32 and 33 below 110 the cords 34 for the purpose of supporting the articles and preventing the same from sagging down between the ropes 34.

A steam receiving chamber 36 is arranged upon the bottom of the reservoirs 5, excepting the two end reservoirs which are not provided with such chambers. Steam may be supplied to these chambers from any suitable source, so that the liquid within the chamber is maintained in a highly heated 115 condition. The bottom of each reservoir is further provided with a suitable drain or outlet 37, and a receiving tank 38 is arranged beneath the presser rollers 19 and 20 to receive the water pressed from the fabric 120 articles, the bottom of said tank being likewise equipped with a drainage opening or outlet 39.

At one side of the machine, opposite to the two forward reservoirs 5 and also op-

posite to the rear reservoir, a hopper 40 is mounted in a suitable support 41 fixed upon the machine frame. In this hopper, a chamber 42 is secured upon one of the side walls thereof, and said chamber is adapted to receive liquid soap, bluing, or other washing compound which is poured into the same through the mouth or inlet spout 43 projecting outwardly from one of the hopper walls. 5 A rock shaft 44 is arranged centrally above the chamber 42 and journaled at its ends in the opposed walls of the hopper. To said shaft, the connected compartments 45 are fixed. Each of these compartments is in the 10 form of an equilateral triangle, the apex of which is suitably secured to the shaft. These compartments, at their upper or wider ends, are open, and said compartments are located in the hopper, approximately entirely 15 out of the vertical line of the chamber 42. To the shaft 44, arms 46 are fixed, and upon the outer ends of said arms, the buckets 47 are hingedly mounted at their closed ends. At opposite ends of the chamber 42, the same 20 is reinforced at its upper edge by rods 48 upon which the respective compartments 45 are adapted to engage and be supported. The bottom wall of the chamber 42 is preferably reinforced for sliding contact of the 25 scoop or bucket 47 therewith. A coil spring 49 acts to force this bucket outwardly into longitudinal alinement with the arm 46, when the bucket is raised above the rod 48. 30 Pipe 50 designates a water supply pipe which is adapted to supply water to the compartments 45, and a steam pipe 51 has its lower outlet end disposed in the chamber 42 whereby the contents of said chamber are heated. A pipe 52 is connected centrally to the bottom wall of the hopper 40 and to the tank or 35 reservoir 5, immediately adjacent to the upwardly moving sections of the series of tapes 13 which pass from the roller 6 and over the guide roller 14 into the next adjacent reservoir. Pipes 53 are also connected to the 40 other reservoirs which are not provided with the compound feeding means above referred to, and supply hot water to said reservoirs from a suitable supply source. The 45 bottom of the chamber 42 is provided with a suitable drain cock 54, whereby the material may be drained from said chamber when necessary. It will be noted that the water supply pipes 52 and 53 are connected to the 50 several reservoirs above the axis of the roller 6 therein. An overflow pipe 55 extends upwardly through the bottom of each reservoir and has its upper end disposed slightly below the axial centers of said rollers. Thus, 55 the water in the several reservoirs is, at all times, maintained at a predetermined and uniform depth.

From the foregoing description, the operation of my improved washing machine will be understood as follows:—The sheets,

towels, table cloths, napkins, and like flat fabric articles, are fed to the machine by placing the same upon the inclined table 18 over the plurality of moving feed tapes or ribbons. These tapes carry the articles in 70 the direction indicated by the arrow and around the first of the rollers 14, at which point the articles are also engaged by the downwardly moving series of cords 26. As the articles are thus carried below the roller 75 14, hot water is forcibly ejected from the pipe 12 by the action of the pump 9 against such articles, so that the fabric is thoroughly permeated by this water and the dirt therein loosened and removed. The engagement of the fabric articles by the corrugated periphery of the roller 6, when there is a slight rubbing action, together with the action of the water constantly circulating through the reservoir, thoroughly removes 80 all particles of dirt from the fabric. This action is repeated in each of the several reservoirs. To the first of the reservoirs, cold soap suds is automatically fed by means of the feeding device hereinbefore described. 85 90 This device is operated by supplying water from the pipe 50 to one of the compartments 45. The weight of this water causes said compartment to move upon one side of the shaft 44, thereby rocking said shaft until 95 the compartment wall strikes upon the rod 48 at the upper edge of the chamber 42 and the water will be discharged into the hopper 40. In this movement of the water chamber, it is obvious that the bucket or scoop 47 100 on one of the arms 46 is moved upwardly upon one side of the chamber 42, and is completely filled with the soap suds in said chamber. When the scoop reaches a point above the upper edge of the chamber wall, 105 the spring 49 acts to force said scoop outwardly so that its contents will be discharged into the hopper 40. The water is continuously supplied from the pipe 50 so that the other compartment 45 will be filled 110 and the above action repeated. There is, thus, a constant supply of water and soap suds from the hopper to the reservoir, and this saponified water is being continually withdrawn from the reservoir by the pump 115 9 and re-supplied thereto in the form of a multiplicity of jets from the pipe 12 which impinge against the fabric articles. To the second of the reservoirs 5, a hot bleaching soap suds is continuously fed from the automatically operating feeding device, while in the third, fourth and fifth reservoirs, the rinsing action takes place, and the soap is removed from the articles by being passed through the hot water contained in said reservoirs. To the sixth and last reservoir, a bluing composition is continuously supplied. 120 From this latter reservoir, the articles are carried by the tapes 13 and finally, after the water is compressed therefrom, fed to the 130

- drying and ironing machine. By the provision of the several centrifugal pumps, a strong current of water is constantly circulating through each of the reservoirs which, 5 by contact with the several articles of fabric passing therethrough, effectually removes the dirt. The reservoirs may be periodically drained and thoroughly cleansed by opening the outlets 37.
- 10 Any preferred driving mechanism may be employed for the operation of the machine; but, preferably, the several pumps are connected in series to a motor or other source of power and directly driven therefrom. The 15 corrugated rollers 6 are driven by chain or gear connections from the shafts of the respective pumps. The several rollers 14, the presser rollers 19, and the rollers 22 and 32, are driven by chains or suitable gearing independently of the pumps and the rollers 6. Preferably, this latter gearing should be capable of such adjustment that the speed of movement of the article feeding tapes 13 can be varied so that a greater or less length 20 of time will be required for such articles to pass through each of the reservoirs, in accordance with the particular condition of the articles which might necessitate a more thorough cleansing action.
- 25 From the foregoing, it will be seen that I have produced a machine for the washing of fabrics which is capable of operating upon lace curtains and like delicate articles without the slightest wear or tear upon the same. By eliminating the necessity of frequent handling of the articles in transferring the same from one machine to another, the labor incident to the operation of such washing 30 machinery is reduced to a minimum.
- 35 While I have shown and described the preferred construction and arrangement of the several elements employed, it is to be understood that the machine is susceptible of considerable modification therein, and I, 40 therefore, reserve the privilege of resorting to all such legitimate changes as may be 45

fairly embodied within the spirit and scope of the appended claims.

Having thus fully described my invention, what I desire to claim and secure by Letters 50 Patent is:—

1. In a washing machine, a series of reservoirs, a friction roller mounted in each of said reservoirs, a plurality of spaced endless flexible tapes having one of their stretches 55 extending through the reservoirs and around the rollers therein, a series of spaced endless flexible holding members having one of their stretches adapted for engagement upon the articles arranged on said tapes at points between the spaced tapes and also movable through the reservoirs around the rollers therein, and a series of endless friction members arranged at one end of the series of tapes and having one of their stretches 60 disposed between the spaced tapes to engage and remove the articles from the tapes.

2. In a washing machine of the character described, a series of reservoirs, a friction roller mounted in each of the reservoirs, 70 means for transferring the articles to be washed successively from one reservoir to another and around the respective rollers, and means for intermittently feeding a 75 cleansing solution to certain of said reservoirs.

3. In a washing machine of the character described, a series of reservoirs, a friction roller mounted in each of the reservoirs, means for transferring the articles to be 80 washed successively from one reservoir to another and around the respective rollers, and gravity actuated means for intermittently feeding a cleansing solution to certain of said reservoirs. 85

In testimony whereof I hereunto affix my signature in the presence of two witnesses.

WALTER J. BRUNGER.
